UNITED STATES PATENT OFFICE.

SAMUEL L. DOERING, OF LINWOOD, KANSAS.

VALVE GRINDER.

Application filed September 22, 1923. Serial No. 664,157.

To all whom it may concern:

Be it known that I, SAMUEL L. DOERING, a citizen of the United States, residing at Linwood, in the county of Leavenworth and

5 State of Kansas, have invented certain new and useful Improvements in Valve Grinders, of which the following is a complete specification.

This invention relates to valve-grinders, 10 and has particular reference to the type of grinder used in grinding or re-facing puppet valve seats of internal combustion engines.

A primary object of this invention is the provision of a grinding tool having a gear 15 member which may be continuously rotated by any suitable means, yet will transmit an oscillating movement to the shaft carrying the valve head engaging means.

Another object of this invention is to provide 20 a valve-grinder that may be operated by hand, by direct worm or helical connection from a motor or by a flexible shaft connection.

A still further object of this invention is 25 the provision of a simply constructed, compact tool having an adjustable valve head engaging means which may be used in connection with all sizes of valves without the customary removal and replacing of another size.

With these general objects in view, as well 30 as minor objects which will appear in the course of the detailed specification, the invention will now be described with reference 35 to the accompanying drawings illustrating three constructions embodying the improvements and designed particularly for operation in the grinding of what are known as puppet valves, after which the novel features 40 of the same will be set forth and defined in the appended claims.

In the drawings:

Figure 1 is a side elevation of the preferred 45 form of the invention with a portion of the cover plate broken away.

Fig. 2 is a section of the valve-grinding tool taken on line II—II of Fig. 1, looking in the direction of the arrow.

50 Fig. 3 is a fragmentary sectional view taken on line III—III of Fig. 2 showing one method of transmitting the driving power.

Fig. 4 is a section of the engaging foot taken on line IV—IV of Fig. 1, looking in the direction of the arrow.

55 Fig. 5 is another section of the engaging foot taken on line V—V of Fig. 3.

Fig. 6 illustrates one modified form of construction, showing the tool adapted to be operated by either hand crank or flexible shaft connection.

60 Fig. 7 is a view of a conventional form of crank.

Fig. 8 is a fragmentary view of the end of a flexible shaft, and

65 Fig. 9 is a section corresponding to that of Fig. 3, showing the use of helical gears for driving.

Referring now to the drawings in detail, wherein similar reference characters designate like parts throughout the several views, 70 10 is a housing, preferably formed of metal, having in the case of the preferred form, a threaded opening 11 for the reception of a co-acting threaded portion 12 of an ordinary electric motor 13. The well known motor 75 shaft 14 has a worm gear 15 rigidly attached thereto and disposed in meshing relation with gear teeth 16 integral with segmental gear plate 17 within the housing. Stub shaft 18, upon which segmental gear plate 80 17 rotates, may be formed integral with housing 10. Two segmental sets of teeth 19 and 20 are carried by gear plate 17 and are adapted to intermittently engage bevel gears 21 and 22 when gear plate 17 is 85 rotated. These gears 21 and 22 are held in operative engagement with the segmental sets of teeth 19 and 20 by a shaft 25 journalled in cover plate 23, which is fastened to housing 10 by screws or analogous means 90 24. Gears 21 and 22 are rigidly attached to shaft 25 and transmit oscillating movement thereto as above described and shown in Figure 1. It is plainly evident from the drawing, that in operating the valve-grinder, gear plate 17 is rotated and teeth 19 engage and rotate gear 21 in a counterclockwise direction for approximately one complete turn and, immediately upon completion of this action, teeth 20 enter into engagement with gear 22 and move it, together with shaft 25, in a clockwise direction for one and one-half turns. This ratio of oscillation is highly desirable in puppet valve 95 grinders of this type, and obviates the customary hand rotation of the entire tool.

100 The desired pressure may be exerted through any suitable handle 26 and, in the case of the modified forms, the rotation motion or power may be transmitted to gear plate 17 by an ordinary crank, as illustrated in Figure 7, adapted to engage shaft 27

through the medium of a squared portion 28 and pin opening 29 provided to receive a cotter or tapered pin. A flexible shaft connection 30, shown in Figure 8, may be used to advantage in the same way, and both methods may be used to rotate helical gears 31 and 32 shown in Figure 9.

Referring at this time to the valve head engaging foot, which is carried and oscillated by shaft 25. This foot comprises a bifurcated body member rigidly attached to shaft 25 by a pin 33 and having depending sides 34. Two slots 35 are provided in the top. Adjustable members 36 possessing oppositely disposed stubs 37 and 38 carried between sides 34 are locked against movement by screws, bolts or like means 39 which pass through slots 40 of the adjustable members 36. Tightening of these screws 40 draw sides 34 tightly together and prevents movement of members 36. To increase or decrease the distance between stubs 38, a flat circular plate 41 may be provided, which is held in engagement with the body member by pin 33 elongated for that purpose. Eccentric arcuate slots 42 cut into plate 41 with their outer ends gradually approaching the periphery of the plate, are adapted to receive stubs 37 and force them apart as plate

41 is rotated in the direction of the arrow 30 (Fig. 4). This motion is reversed when it is desired to bring the stubs closer together again. Quick adjustment for different size valve-heads is reached through this construction, and a most desirable result is attained.

Having described the invention, what is claimed is:

In a valve-grinder, an adjustable valve head engaging foot mounted on the shaft 40 thereof, comprising a pair of slotted stub members each having an upwardly and a downwardly disposed stub, a housing having a pair of aligned radial slots in the top thereof and downwardly disposed side walls, locking means for each of said stub members carried by said housing side walls and passing through the slots of said stub members, said upper stub of the stub member passing upwardly through said housing slots and means engaging said upper stubs for imparting rectilinear movement to the entire stub member, whereby the distance between said lower stubs may be increased or diminished.

In witness whereof I hereunto set my signature.

SAMUEL L. DOERING.
